GRINDING MACHINE FOR CRANK SHAFTS

Filed Dec. 27, 1930

INVENTOR
HANS JØRGEN EPIKSEN
BY Richardsg. Geier
ATTORNEY

UNITED STATES PATENT OFFICE

HANS JØRGEN ERIKSEN, OF AARHUS, DENMARK

GRINDING MACHINE FOR CRANK SHAFTS

Application filed December 27, 1930. Serial No. 505,050.

The present invention relates to improvements in grinding machines for crank shafts, preferably such crank shafts that have two, four, six or more double shafts and which are employed in rapidly rotating engines as for instance automobile engines. The journals of such crank shafts are quickly worn oval, and therefore necessitate a turning or grinding to be made cylindrical again.

10 The clamping of such a crank shaft in a lathe requires special tools, which increase the cost of the operation considerably. The grinding of the journals may be effectuated in a turning lathe or on a specially constructed 15 machine, the first method requiring expensive tools, and the latter special grinding machines.

The machine according to the invention may be produced at a price that allows even 20 smaller workshops to obtain one. It is a well known fact that the smaller workshops usually have no special appliance for grinding crank shaft journals, and for this reason they omit the work even though it be greatly 25 needed. As furthermore automobile repairs have to be executed quickly there is no time to send the crank shaft to a specially equipped shop for grinding, and when the complaint is really bad the crank shaft is renewed at high 30 costs. If, however, a workshop is provided with a grinding machine, the crank shaft may quickly be reground at a reasonable cost.

The characteristic feature of the invention is that the crank shaft is clamped in the 35 grinding machine resting on two of its journals, which are in line with each other. These journals lie in two bearings slidably mounted on a slide. The one bearing carries a grinding disc protruding through an opening in 40 the bearing and rotating in a direction longitudinal to the crank shaft journals. The other bearing supports the other journal of the crank shaft. To the journal that is not being ground is attached a pulley driven by 45 a cord from an axle rotating in such a manner that the crank shaft rotates during the grinding process. Furthermore there is a kind of tension roll in connection with the aforesaid pulley, which is arranged in such a manner 50 that the cord drive causes the journal to journal.

remain in the same position in the bearing.

The grinding disc is so proportioned that it may bear in upon the crank shaft between the two arms that limit the double crank shaft and is journaled in a system of slides, to allow the adjustment of the grinding stone in several directions in relation to the rotating journal and is clamped in towards this journal allowing the grinding off of any uneven portion, leaving the journal finally precisely 60 round.

Upon this device two, four, six or more journaled crank-shafts may be ground, as long as two and two of the journals have a common centre axis, because the two journals rotate in two bearings during the grinding process, the one being ground while the other serves to rotate the crank-shaft. A special device is arranged in the former bearing to prevent a lateral movement of the 70 crank-shaft while being ground.

The invention is illustrated in the accompanying drawing where

Fig. 1 is a front elevation of the device,

Fig. 2 a top elevation of same,

Fig. 3 a sectional cut through same,

Fig. 4 the hub for the driving cord,

Fig. 5 a sectional view of the grinding disc,

Fig. 6 a side view of the bearing in which the grinding takes place.

Fig. 7 a side view of the bearing to which the driving means for the crank-shaft are carried, and

Fig. 8 a top elevation of the bearing shown in Fig. 6.

The machine comprises a base 1 provided in the one side with a long slide 2, carrying two slidable bearings 3 and 4. The bearing 3 serves to hold the crank-shaft journal 5, while the bearing 4 carries the crank-shaft journal 6. The crank-shaft 7 is clamped in position as illustrated in Figs. 1 and 2 in such a manner that the two journals 5 and 6, the centre lines 8 of which are in prolongation of each other and thus common, lie each in a bearing in which they rotate. The one journal 6 carries at the same time a cord pulley by means of which the crank-shaft is rotated, whereas the grinding takes place on the other 95 100 journal.

The driving power may be taken for instance from an electromotor 9 fitted with pulleys 10 from which a cord 11 is carried over to the other pulleys 12 on the spindle 13 of the grinding disc. This spindle 13 runs in ball bearings 14 on a vertical slide 15, which by means of a handle 16 journaled at the one end in a post 44, may be adjusted up or down. By means of another slide 17 and hand-wheel 18 the spindle 13 is adjustable in towards or out from the journal 5, while a third slide 19 with hand-wheel 20 allows the spindle 13 to be adjusted laterally, that is parallel to the longitudinal direction of the journals.

As will be seen from the drawing particularly Fig. 2 the driving shaft carries a third pulley 45 which through a cord 46 drives a pulley 47 attached to a worm shaft 48 engaging a worm on a long shaft 23. In Fig. 1 the worm 21 and the worm wheel 22 are indicated by dotted lines. The shaft 23 is arranged parallel with the slide 2 and is journaled in a bearing 24 in the bearing 4. It carries a pulley 25 which by means of a cord 49 is connected to a pulley 26 clamped to the journal 6. The cord 49 is continued over a rearwardly projecting pulley 50 rotatably mounted in an arm 51 on the bearing 4, to the effect that the cord 49 will endeavour to secure the position of the journal 6 in its bearing 4.

The details of the construction of bearings 3 and 4 are shown in Figs. 6 and 7. The bearing 3 has an angular cutting 27 in which the journal rests. It is held in position by means of two arms 28 that may be attached to the bearing 3 by means of a stud 29, which clamps together two ball sockets 30, one on each side of each arm, and by this is attained that the arms 28 may be brought to straddle more or less. These arms 28 serve partly to hold the journal 5 in the bottom of the angular cutting 27 and partly to abrogate the lateral movement of the crank-shaft, because the arms 28 are pressed out against the journal arms as shown in Fig. 2.

Below the journal 5 rests upon a steel block 31, which is clamped to the bearing by means of a bolt 32 in an elongated slot 33, thus allowing the steel block 31 to slide forwards and backwards, gliding over two pins 52. It may be replaced by another corresponding to the diameter of the crank-shaft journal 5, as these vary in different kinds of motors. The steel block 31 can thus be of varying height and must not project too far forward as shown in Fig. 6. The other bearing 4 is made in a similar manner. It is provided with an angular cutting 34 for the journal 6, the angular cutting being provided with tempered steel blocks 35 upon which the journal rotates. Both the bearings 3 and 4 are made of steel plate and at their lower end cast in one with a slide 36 on the runners 2 on the frame. The slide 36 and the bearing 4 have each a

placket 37 and 38, which may be clamped together around the runner 2 by means of a screw spindle 39 and hand wheel 40 to be held in any desired position.

In the foregoing it has been mentioned that the crank-shaft journals 5 and 6 rotate during the grinding process. The journal 6 is held down in its bearing by means of the cord 49 as shown in Fig. 7 and described in the foregoing.

The other bearing 3 is open at front as shown in Fig. 6, and here the grinding disc 41 operates. This disc rotates in a direction parallel to the longitudinal direction of the journal, and has in the middle a hollow 42 for a spindle nut 43 engaging the spindle 13 as seen in Fig. 5.

The cord pulley 26 is bipartite and gathered by means of two clamp screws 52, see Fig. 7. In the hub 53, see Fig. 4 as well, there are inserted three clamp screws 54 that may be clamped in towards the centre, allowing an adjustment for journals of different diameters. Beside the screw heads there is a scale 55 for adjusting the screw to fit any size of journal for instance if the screws are to clamp a journal of 50 mm. in diameter, the three screws 54 are screwed so far down that their heads are immediately opposite the figure 50 on the scale. The screws then fit exactly to this diameter. The two parts of the cord pulley may quickly be clamped to the journal 6 by means of the two screws 52.

The operation of the device is easily understood. In a crank-shaft that has been in use some time the journals are worn somewhat oval, and after being ground on the machine are precisely circular.

The two journals with centre line in common are placed one in each bearing. The motor is started rotating the grinding disc 41 which then grinds the rotating journal 5. During this process care must be taken that the pressure of the grinding disc 41 against the journal increases gradually and laterally to cover the entire surface of the journal, as likewise it is moved up and down by means of the handle 16, to allow the hollow grinding disc to engage the entire journal for the removal of any projecting parts thereon.

After grinding the journals are polished with any suitable means.

The constructive details of the device may be altered in many different ways without therefor deviating from the scope of the invention.

Having now described my invention what I claim as new and desire to secure by Letters Patent is:

1. A grinding machine for crank shafts, including a slide, two bearings for any two crank shaft journals in alignment adjustable laterally thereon, a rotatable grinding disc protruding through an opening formed in one of said bearings, a spindle carrying the

- grinding disc, ball bearings for this spindle arranged in a vertical slide, and a handle bar for raising or lowering the grinding disc in the slide, at a right angle to the vertical slide, a horizontal slide, a screw spindle and handle wheel attached thereto for horizontal adjustment of the grinding disc, means for rotating the grinding disc and means for rotating the crank shaft in the bearing.
- 10 2. A grinding machine for crank shafts, including a slide, adjustable thereon two bearings, for two crank shaft journals a grinding disc operating through an opening in the one of these bearings, means for adjusting 15 the grinding disc vertically and horizontally, means for rotating the grinding disc and in connection herewith a shaft parallel with the said slide, and a worm gearing thereon for transmitting the rotation from a driving 20 engine to the shaft, a pulley on the shaft engaging a bipartite pulley on the crank shaft journal in the other bearing, a rearwardly arranged pulley engaging the aforesaid pulleys to the effect of holding the crank shaft journal in its bearing during simultaneous rotation.
